UNITED STATES PATENT OFFICE.

ALBERT EDWARD SIMONS AND EDWARD HIXON, OF CHICAGO, ILLINOIS.

WATER-HEATER.

SPECIFICATION forming part of Letters Patent No. 567,868, dated September 15, 1896.

Application filed April 15, 1896. Serial No. 587,666. (No model.)

To all whom it may concern:

Be it known that we, ALBERT EDWARD SIMONS and EDWARD HIXON, of Chicago, in the county of Cook and State of Illinois, have 5 invented a new and Improved Water-Heater, of which the following is a full, clear, and exact description.

The object of the invention is to provide a new and improved water-heater which is simple and durable in construction, and more especially designed for heating feed-water for boilers in a very simple and economical manner by the use of live steam or exhaust-steam, or both.

15 The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

25 Figure 1 is a sectional side elevation of the improvement. Fig. 2 is an enlarged perspective view of the live-steam outlet-cap, and Fig. 3 is a like view of the water-inlet and exhaust-steam outlet-cap.

The improved water-heater is provided with a pipe A, connected with a pump, water-main, 30 or other suitable source of water supply, said pipe being connected with a cap B, held on the outer end of a water-pipe C, preferably made in the form of a coil, as is plainly indicated in Fig. 1, said pipe discharging at its 35 upper end into a cap D, connected by a pipe E with the boiler, to deliver the heated water to the same. The exhaust-steam pipe F passes centrally through the cap D and centrally through the coil C, so that the exhaust-steam 40 travels in the inverse direction to that of the water passing through the coil.

The pipe F is provided near the entrance of the cap D with an oil-separator G, containing a deflecting-plate G' and a corrugated 45 baffle-plate G'', on which the oil accumulates and flows down by gravity into a receptacle H, provided with a gage H' and a draw-off cock H'' for emptying the vessel H from time to time of the accumulated oil. Next to the oil- 50 separator G is arranged a valve F' in the pipe F for shutting off the exhaust-steam whenever desired. The exhaust-pipe F passes cen-

trally through the cap B at the lower end of the coil C, to then connect with a vertically-disposed exhaust-pipe I, having its upper 55 branch I' discharging into the atmosphere, the said branch I' being adapted to be closed by a valve I'' to cause the exhaust-steam to pass downward into a branch I'' and from the latter by a pipe J to a steam-trap K, of any approved construction.

The lower end of the branch I'' is provided with two valves I⁴ I⁵, and the extreme lower end of said pipe is adapted to discharge into a sewer or other place. The pipe I'' between 65 the valves I⁴ I⁵ is connected by a pipe L with a receiver N for receiving the water of condensation, the said receiver being provided with an outlet-pipe N', adapted to connect with a pump for forcing the water in and 70 through the pipe A, to return the water of condensation to the boiler by said pipe A and the water-pipes C and E. The receiver N is also provided with a valved outlet N'', adapted to connect with the city main or other source 75 of water supply for supplying the receiver N with water in case a vacuum exists therein.

The water-pipe C is surrounded by a steam-pipe O, which may serve as a steam-jacket 80 and which is adapted to connect with a live-steam pipe P to pass said steam through the said pipe O in the inverse direction of the flow of the water passing through the pipe C. The live-steam pipe P is provided with a valve P' and is adapted to be connected with a 85 branch pipe P'', having a valve P''³, connected with the exhaust-steam pipe F, so that by closing the valve P' and opening the valve P''³ part of the exhaust-steam may be passed 90 through the branch pipe P'' into the pipe O to assist in heating the water flowing through the pipe O. The lower end of this steam-pipe O terminates in a cap Q, provided with an outlet-pipe R, connected with the pipe J, for passing the steam to the trap K. The pipe R 95 is provided with a downward extension R', discharging into the pipe L, leading to the receiver N, so that any water of condensation can pass through the said pipe R to the pipe L and to the said receiver N.

In the pipe L are arranged the valves L' and L'', on opposite sides of the pipe R', to permit of running the water of condensation either to the receiver or condensers N or to

the lower end of the pipe I³, connected with the sewer.

The pipe J is provided with two valves J' J² on opposite sides of the pipe R to permit 5 of controlling the flow of the steam or water of condensation to either the trap K, receiver N, or pipe I. The trap K is provided with an outlet-pipe S, having a valve S', controlled by a float S² in the said trap K, so that when 10 the water rises therein the float S² will open the valve S' to permit the accumulated water to pass out through the pipe S, either to a suitable place of discharge or through a branch pipe T into the reservoir N. The 15 pipe S is provided with a valve S³, and a similar valve T' is arranged in the branch pipe T for controlling the flow of water either to the outside or to the reservoir N. Now it will be seen that by the arrangement described 20 the water to be heated flows in one direction, while the steam surrounding the water-pipe and the steam passing in a pipe through the water-pipe flow in opposite directions, so that the feed-water is gradually heated, as 25 it first is subjected to the steam having a low degree of temperature, and is finally subjected to steam of a high degree of temperature, so that when the feed-water reaches the cap D it is at a very high temperature. Now 30 it will be seen that by the arrangement described live steam and exhaust-steam can be used for heating the feed-water in the manner described, or, if desired, the live steam can be shut off and exhaust-steam passed 35 both through the inner pipe F and the outer or check pipe O.

Having thus fully described our invention, we claim as new and desire to secure by Letters Patent—

40 1. A water-heater, comprising a water-pipe connected with a suitable source of water supply and with the boiler, a steam pipe or jacket surrounding said water-pipe, a steam-pipe passing through said water-pipe, the 45 steam passing through said pipes flowing in an opposite direction to the flow of the water passing through the water-pipe, a live-steam pipe connected with one end of said outer steam-pipe, and an exhaust-pipe connected 50 with the said inner steam-pipe, substantially as shown and described.

2. A water-heater, comprising a water-pipe connected with a suitable source of water supply and with the boiler, a steam pipe or 55 jacket surrounding said water-pipe, a steam-

pipe passing through said water-pipe, the steam passing through said pipes flowing in an opposite direction to the flow of the water passing through the water-pipe, a live-steam pipe connected with the said outer steam-pipe, 60 an exhaust-pipe connected with the said inner steam-pipe, and a water-receiver adapted to be connected with the outlets of said steam-pipes, to receive the water of condensation, substantially as shown and described. 65

3. A water-heater, comprising a water-pipe connected with a suitable source of water supply and with the boiler, a steam pipe or jacket surrounding said water-pipe, a steam-pipe passing through said water-pipe, the 70 steam passing through said pipes flowing in an opposite direction to the flow of the water passing through the water-pipe, a live-steam pipe connected with one end of said outer steam-pipe, an exhaust-pipe connected with 75 the said inner steam-pipe, a steam-trap adapted to be connected with the outlets of the said steam-pipes, a receiver adapted to be connected with the outlets of said steam-pipes, and means for controlling the flow of 80 the steam and water of condensation to said trap and receiver, substantially as shown and described.

4. A water-heater, comprising a water-pipe adapted to be connected with a source of water 85 supply and with a boiler, a live-steam pipe or jacket surrounding the water-pipe, an exhaust-steam pipe passing through said water-pipe, a steam-trap connected with the outlets of the steam-pipes, and a water-receptacle 90 adapted to be connected with the outlets of the said steam-pipes and with the trap, substantially as described.

5. A water-heater, comprising a water-supply pipe, a live-steam pipe or jacket surrounding the water-pipe, an exhaust-steam pipe passing through the said water-pipe, a steam-trap, a valved pipe connecting the trap with the outlets of the said steam-pipes, a receptacle for the water of condensation, a valved 95 pipe connecting the receptacle with the said outlets, and a valved pipe connecting the trap with the receptacle, substantially as described. 100
